ABSTRACT: A valve for emptying boilers has a locking member for the liquid phase and a locking member for the gas phase, the two members being coaxial and being operated by a common actuating device against the action of closing springs. The locking member for the liquid cooperates with a valve seat fixed to the bottom of the boiler. The valve is particularly characterized in that the locking member for the liquid is provided with a central flow passage for the gas phase. A fixed tube joint for gas flow is seal tightly connected to the passage from the boiler interior. A fixed tube joint for gas outflow is also connected from the outside to the passage. The two points permit a relative movement of the locking member for the liquid. The locking member for the gas is located in this passage. The common actuating device engages the locking member for the gas.

VALVE FOR EMPTYING BOILERS

DESCRIPTION OF THE INVENTION

This invention relates to a valve for emptying boilers and refers more particularly to a valve of this type having a locking member for the liquid phase and a locking member for the gas phase, the two members being coaxial and being operated by a common actuating device against the action of closing springs, the locking member for the liquid phase cooperating with a valve seat fixed to the bottom of the boiler.

An advantage of such a valve consists in that the liquid phase as well as the gas phase of the boiler contents can be withdrawn through one valve, instead of using two separate valves.

A valve of this type is known in prior art, but it has a very complicated structure and the valve casing consists of a casting which is difficult to make. The machinery of this valve is difficult and expensive, since the machining operations must be carried out along different axes which are shifted and inclined relatively to each other, so that the use of special clamping tools cannot be avoided.

Furthermore, a substantial drawback of the prior art device consists in that the common valve spindle of the two locking members extends from the inflow space of the gas locking member in which there is full boiler pressure, through a casing wall and into the outflow channel of liquid locking member which has actually atmospheric pressure when the locking members are closed. It is therefore necessary to seal at this location the full boiler pressure against the atmosphere by means of a movable packing, since the valve spindle must be movable axially. There is an operational danger due to this uncertainty of a proper seal.

Finally this valve cannot be worked from the bottom, so that it is necessary to climb into the boiler for that purpose.

An object of the present invention is the provision of a valve for emptying boilers which will not have the drawbacks of prior art devices, which has a simple construction, a good machinability and availability from and to the bottom and which will avoid the above-mentioned sealing problem.

Other objects of the present invention will become apparent in the course of the following specification.

In the accomplishment of the objectives of the present invention it was found desirable to provide the locking member for the liquid with a central flow passage for the gas phase to which are airtightly connected a fixed tube joint for gas flow from the boiler side and a fixed tube joint for gas outflow from the outside, the two joints permitting a relative movement of the locking member for the liquid. The locking member for the gas is situated in the passage provided in the locking member for the liquid. An actuating device common to both members engages the locking member for the gas.

Then the sealing of the boiler takes place only through the two locking members. Only the movable seals at the inlet and outlet of the flow passage have the task of preventing the mixing of the liquid phase with the gas phase during the emptying of the boiler. They do not participate in the locking of the boiler.

According to a further feature of the present invention the mixing of the liquid phase with the gas phase can also be prevented by sealing the inlet and outlet of the flow passage in or by muffs sliding in sockets for the inflow and outflow of gas. This also provides a good guide for the locking member for the liquid.

According to a further feature of the present invention the correctly adjusted arrangement of the gas inflow socket may be provided by using a cage which is firmly connected with the valve, which extends bell-like over the locking device for the liquid and which serves as a spring support and for fixing the gas flow socket provided inside the boiler.

A further feature of the present invention consists in that the valve seats with their locking members as well as the cage with the gas inflow socket constitute a structural unit and are fixed in a downwardly extending manner to the bottom of the

boiler, while the other valve part having the outflow passages as well as the actuating mechanism is screwed with a ring joint to the flange of the valve seat or is directly screwed to the bottom of the boiler. This makes it possible to operate the entire valve from the bottom and also provides an easy exchange of the valve parts consisting of outflow passages and the actuating mechanism, so that when an outflow channel is damaged it can be replaced without moving the locking members into an open position or even taking them apart, which would make necessary the emptying of the boiler.

The invention will appear more clearly from the following detailed description when taken in connection with the accompanying drawing the sole FIGURE of which is a section through a valve constructed in accordance with the principles of the present invention.

The drawing shows a boiler bottom 1 carrying an emptying valve provided with a member 2 for liquid locking and a member 3 for gas locking which is coaxial to the member 2. The two members are actuated against the action of closing springs 4, 5 by a suitable common actuating device only the rod 6 of which is shown in the drawing.

The member 2 for the liquid cooperates with a valve seat 7 fixed to the bottom of the boiler. An outflow passage 8 extends to the valve seat. The member 2 is provided centrally with a flow passage 9 for the gas phase. A gas inflow joint 10 extends from the interior of the boiler and a gas outflow joint 11 extends from the outside. The two joints participate in the flow passage and are fixed to the valve. For that purpose the inlet and outlet ends of the passage 9 are provided with muffs 12 and 13 which are sealed by O-rings 14 and 15 and which slide upon the joints 10 and 11.

The gas withdrawing joint 11 forms a gas outflow passage 16 of the valve, while the gas inflow joint 10 is connected with a gas supplying pipe 17 which extends upwardly above the level of the liquid within the boiler. The gas supply joint 10 is fixed to a cage 18 which extends bell-like over the member 2 for liquid locking. The cage 18 is firmly connected with the valve and serves at the same time as a support for the locking spring 4.

The gas locking member 3 is provided directly at the flow passage 9 of the member 2 for liquid locking and is shaped as an axially movable valve plate which cooperates with the construction 20 of the flow passage 9 serving as valve seat 19. The flow passage 9 has a spoke cross 21 used to limit the stroke of the valve plate 3 and as a support for its closing spring 5. The member 21 is also provided with radial ribs 22 used to guide the valve plate which is engaged by the actuating rod 6.

The valve seats 7 and 19 with their locking members 2 and 3, as well as the cage 18 with the gas inflow joint 10 are all combined into a single structural unit extending into the interior of the boiler and are connected by a flange 23 with the bottom 1 of the boiler so as to be accessible from below. The remaining valve portion consisting of the outflow passages 8 and 16 with the outflow joint 11 and the actuating mechanism with actuating rod 6 are all centered by an annular band 24 screwed to the flange 23.

The locking members 2 and 3 are opened and closed one after the other by the actuating rod 6. First the gas locking member 3 is opened, whereby the liquid locking member 2 is initially continued to be held in its closed position by its spring 4. After the gas locking member 3 has reached its maximum stroke position and engages the crossmember 21 in the flow passage 9, the liquid locking member 2 will be opened during further stroke movement of the actuating rod 6. The closing takes place in reversed sequence. As is known, the earlier opening of the gas locking member has the purpose to provide a drop in pressure in the boiler before the emptying or to provide pressure balance between the boiler and the container which is to be filled when there is a gas pendulum conduit between the gas outflow passage in the emptying valves of the boiler and that container. This simplifies the emptying and the filling procedures.

I claim:

1. A valve for emptying a boiler, comprising a locking member for the liquid phase, said member having means forming a central flow passage for the gas phase, a gas supply joint extending from the interior of the boiler and connected to said means, a gas outflow joint extending outside the boiler and connected to said member, said member being movable relatively to said joints, a locking member for the gas phase located within said passage and means actuating both members connected to the locking member for the gas phase.

2. A valve in accordance with claim 1, wherein said means comprise a muff located adjacent one end of said passage and slideable relatively to the first-mentioned joint and another muff located adjacent the other end of said passage and slideable relatively to the second-mentioned joint.

3. A valve in accordance with claim 2, wherein the second- 15

mentioned muff comprises a constriction constituting a valve seat, said locking member for the gas phase consisting of a valve plate adapted to engage said valve seat.

4. A valve in accordance with claim 3, comprising a cage extending bell-like over the locking member for the liquid phase and connected with the gas supply joint.

5. A valve in accordance with claim 4, wherein said two locking members have separate valve seats, said two locking members with their valve seats, said cage and said gas supply joint constituting a single structural unit, said valve further comprising a flange connecting said structural unit to the bottom of the boiler, means having outflow channels and an annular band, and a flange connecting said annular band with said cage.
